UNITED STATES PATENT OFFICE

HENRY WILLIAM SAMUEL PALMER, OF BIRCHINGTON-ON-SEA, ENGLAND

CRATE

Application filed November 2, 1928, Serial No. 316,789, and in Great Britain December 8, 1927.

This invention relates to crates such as are used for carrying bottles of milk, beer or other liquids.

Usually such crates are constructed so that 5 the bottles all stand upon the base side by side and are separated one from the other by partitions.

According to my invention I provide a 10 crate where bottles are disposed in tiers one above the other one row or tier being separated from the one above it by means of a preferably movable tray or partition and the invention may be said to consist broadly of a 15 crate for bottles comprising a rectangular skeleton frame divided vertically into tiers by horizontally disposed partitions between which the bottles are carried.

In the accompanying drawings I have illustrated an embodiment of my invention 20 Figure 1 being a front elevation of a crate constructed according to my invention, Figure 2 is a plan view thereof and Figure 3 a side elevation thereof.

Referring to these drawings the numeral 25 1 designates a frame of substantially rectangular form in side elevation and having vertical side members 2, and the bottom member 3 of this frame may be provided with recesses to position the first row of bottles. I 30 provide, however, any desired number of partition plates 4 preferably in the form of trays shaped and adapted to interlock loosely with and slide along the side members 2 of the frame as a whole and rest upon the tops 35 of the bottles in the row beneath and instead of providing recesses in the bottom member of the frame I prefer to arrange a member 4a similar to one of these plates or trays 4 and secured to the frame by screws 4b. Each 40 succeeding row of bottles stands upon the partition plate 4 dividing it from the row immediately beneath it and the weight of the used row of bottles serves to hold the lower row firmly in position, the flanges on the 45 front and rear edges of the movable partition plates 4 being arranged to extend as shown in Figure 1 over the side members 2 of the crate so that they cannot be completely detached from the frame sideways.

50 The crate may be completed by a top tray 4

adapted either to rest upon or fit over the necks of the bottles. Rollers, indicated at 5, may be provided on the bottom member 3 to enable the crate to be trundled, and rollers or flanged wheels 6 may be provided at 55 the tops of the side members 2 to enable the crates to be run along suspension rails.

As a convenient means for suspending the plates 4 when not in use, a series of recesses 2a are provided in the edges of the side member 2 for holding them as indicated in chain lines.

The whole of the rows or tiers of bottles and the horizontal partition plates 4 are held 60 against undue vibration by means of a spring 7 hinged at one end to the top of one of the vertical side members 2 and adapted at its 65 other end to enter a recess in the opposite side member.

It will be found that a crate of the foregoing character can be cheaply made, and more easily handled than ordinary crates while a greater number of bottles can be accommodated in a given space than with the usual construction. Moreover, the invention 70 lends itself to construction in metals such as duralumin.

What I claim and desire to secure by Letters Patent is:—

1. A crate for bottles comprising a rectangular skeleton frame for holding tiers of bottles, and a multiplicity of horizontal partition plates for separating the tiers by resting on the bottles in one tier while supporting those in the tier above, and means for preventing the removal of the horizontal plates laterally from the crate and so that when not in use they can be moved to and from the horizontal position without being completely detached from the crate. 80

2. A crate for bottles comprising a rectangular skeleton frame, horizontal partition plates slidable upon the vertical sides of the frame, so that such partition plates when the crate is in use, rest upon the tops of one row or tier of bottles and the bottoms of the bottles in the row or tier above rest upon the upper face of the same partition plates. 95

3. A crate for bottles according to claim 2, wherein slots are provided in the edge of 100

the upper part of the vertical side members of the frame adapted to form a means for suspending the partition plates not in use.

4. A crate according to claim 2 having a spring member hinged at one end to the top of one of the vertical side members of the frame and adapted to be connected to the other vertical side member of the frame so as to hold the whole of the rows or tiers of bottles and the horizontal partition plates against undue vibration.

In witness whereof I affix my signature.
HENRY WILLIAM SAMUEL PALMER.
